CLAIM

The ornamental design for a trim table assembly, as shown and described.

DESCRIPTION

FIG. 1 is a perspective view of a trim table assembly showing my new design;

FIG. 2 is a front view thereof that mirrors the rear view;

FIG. 3 is a left view thereof that mirrors the right view;

FIG. 4 is a bottom view thereof;

FIG. 5 is a top view thereof;

FIG. 6 is a cross-sectional view taken along line 6-6 in FIG. 5; and,

FIG. 7 is an exploded perspective view of the trim table assembly.
